United States Patent Office

Des. 193,743
Patented Oct. 2, 1962

193,743

PRINTING MACHINE

John A. Maul, Lyndhurst, and John J. Van Acker, Cheshire, Ohio, assignors to Addressograph-Multigraph Corporation, Cleveland, Ohio, a corporation of Delaware

Filed Dec. 14, 1961, Ser. No. 67,904

Term of patent 14 years

(Cl. D64—11)

Fig. 1

Fig. 2

Fig. 3

Fig. 4

FIG. 1 is a front perspective view of a printing machine showing our new design;

FIG. 2 is another front perspective view thereof turned at an angle of about 90°;

FIG. 3 is a side elevational view; and

FIG. 4 is a rear perspective view thereof.

The dominant features of the design reside in those portions shown in full lines.

We claim:

The ornamental design for a printing machine, substantially as shown and described.
